UNITED STATES PATENT OFFICE.

MARQUIS LAFAYETTE CRAWFORD, OF OSCEOLA, ARKANSAS.

AUTOMATIC TRAFFIC SIGNAL FOR STREET CROSSINGS.

Application filed August 1, 1924. Serial No. 729,569.

It is a purpose of the present invention to provide, in an automatic traffic signal for street crossings, a mechanism, mechanically operated, for turning the signal for displaying "Go" or "Stop", thereby doing away with a crossing policeman.

Another purpose is to provide an apparatus of this kind which is entirely automatic throughout the entire day, it being the purpose to adjust the mechanism so that the signal will turn every half or whole minute or minute and a half, it depending entirely upon the maximum amount of traffic passing the crossing. For instance, if the traffic is substantially heavy, it is possible to adjust the mechanism to turn the signal every minute and a half or every two minutes, it having been previously determined the amount of time which may be required to permit substantially heavy traffic to pass. However, the present construction is designed to permit the signal to change approximately every minute.

Still another purpose is the provision of an operating mechanism including an alarm to be sounded indicating that the signal will change immediately, thereby giving the operators of automobiles an opportunity to prepare to proceed.

The invention comprises further features and combinations of parts to be hereinafter set forth, shown in the drawings and claimed.

In the drawings:

Figure 1 is a view in side elevation of an automatic traffic signal embodying the invention.

Figure 2 is a diagrammatic view of a street crossing and the operating parts of the signal.

Figure 3 is a longitudinal sectional view of the signal mechanism.

Figure 4 is a horizontal sectional view on the plane indicated by the line 4-4 of Figure 3.

Figure 5 is a vertical sectional view on the plane indicated by the line 5-5 of Figure 4.

Referring to the drawings, it will be noted that the signal staff 3 is rotated mechanically, and to accomplish this, a casing 1 is provided having in bearings thereof two shafts 48 and 49 which are rotatable in opposite directions, and to accomplish this, the shaft 49 has two grooved pulleys 50 and 50^a and the shaft 48 a grooved pulley

51. The pulley 50 is connected to the pulley 51 of the shaft 48 by means of a twisted round belt 52, while the pulley 50^a is connected by a belt 53 to a motor 54. Mounted in the casing 1 on pivots 55 are oscillating levers 56 and 57, the remote ends of which carry brackets 58 supporting pins 59, adjustable by means of the nuts 60. The pins 59 are threaded and adjustably carry weights 61 to be held in set positions by set-screws 62. The weights may be adjusted or the pins 59 may be adjusted.

Also, the remote ends of the levers 56 and 57 carry rollers 63 which ride upon the peripheries of disks 64 and 65. These disks have segmental cut-away portions 66 and 67. The disks are so positioned that the cut-away portions will permit the levers 56 and 57 to alternately oscillate. The adjacent ends of the levers 56 and 57 terminate in cams 68 and 69 which cooperate with a roller 70 on one arm 71 of a segmental lever 72 which has a segment gear face 73 meshing with a pinion 74 on a signal staff 3. The adjacent ends of the levers 56 and 57 are positioned side by side so that, when the lever 56 oscillates, its cam 68 will move the arm 71 of the segment lever in one direction, and when the lever 57 oscillates, its cam 69 will move the arm of the segment lever in the opposite direction, thereby imparting an intermittent back and forth rocking movement to the signal staff.

Each of the shafts 48 and 49 carries a disk 75 constructed of insulating material, such as hard rubber, provided with a metal band 76 on its hub having a groove 77. A collector ring 78 engages the groove and is, in turn, connected to an alarm bell 79. A brush 80 plays over the periphery of each disk 75, the periphery of which has a metal segment 81, the brush being connected to a source of supply which, in turn, is also in circuit with the bell. As the shafts 48 and 49 rotate and the levers 56 and 57 alternately oscillate for moving the segment lever and rotating the signal staff, the alarm bells are sounded, indicating that the signal will change.

The invention having been set forth, what is claimed is:

1. A traffic signal for street crossings embodying a turnable staff provided with signal blades bearing signal indicia, a lever having an operative connection with said staff for turning it first in one direction and then

- in the other upon rocking movement being imparted to the lever, and a plurality of gravity actuated levers operatively connected with the first said lever for rocking the latter in opposite directions, and elevating means for said gravity actuated levers.
2. A traffic signal for street crossings embodying a turnable staff provided with signal blades bearing signal indicia, a lever having an operative connection with said staff for turning it first in one direction and then in the other upon rocking movement being imparted to the lever, and a plurality of gravity actuated levers operatively connected with the first said lever for rocking the latter in opposite directions, and elevating means for said gravity actuated levers, said gravity actuated levers being provided with weights adjustable toward and away from their fulcrums.
3. A traffic signal for street crossings embodying a turnable staff provided with signal blades bearing signal indicia, a lever having an operative connection with said staff for turning it first in one direction and then in the other upon rocking movement being imparted to the lever, and a plurality of gravity actuated levers operatively connected with the first said lever for rocking the latter in opposite directions, and elevating means for said gravity actuated levers, said gravity actuated levers having their fulcrums disposed in planes on opposite sides of the first said lever and the elevating means comprising rotatable disks with which the remote extremities of said gravity actuated levers have peripheral contact, said disks having sectors removed to permit the remote extremities of the gravity actuated levers to drop, the disks being operatively connected for synchronous movement in opposite directions.
4. A traffic signal for street crossings embodying a turnable staff provided with signal blades bearing signal indicia, a lever having an operative connection with said staff for turning it first in one direction and then in

the other upon rocking movement being imparted to the lever, and a plurality of gravity actuated levers operatively connected with the first said lever for rocking the latter in opposite directions, and elevating means for said gravity actuated levers, said gravity actuated levers having their fulcrums disposed in planes on opposite sides of the first said lever and the elevating means comprising rotatable disks with which the remote extremities of said gravity actuated levers have peripheral contact, said disks having sectors removed to permit the remote extremities of the gravity actuated levers to drop, the disks being operatively connected for synchronous movement in opposite directions.

5. A traffic signal for street crossings embodying a turnable staff provided with signal blades bearing signal indicia, a lever having an operative connection with said staff for turning it first in one direction and then in the other upon rocking movement being imparted to the lever, and a plurality of gravity actuated levers operatively connected with the first said lever for rocking the latter in opposite directions, and elevating means for said gravity actuated levers, said gravity actuated levers having their fulcrums disposed in planes on opposite sides of the first said lever and the elevating means comprising rotatable disks with which the remote extremities of said gravity actuated levers have peripheral contact, said disks having sectors removed to permit the remote extremities of the gravity actuated levers to drop, the disks being operatively connected for synchronous movement in opposite directions.

In testimony whereof he affixes his signature.

MARQUIS L. CRAWFORD.
